UNITED STATES PATENT OFFICE.

KARL TESSKY, OF ESSLINGEN-ON-THE-NECKAR, GERMANY.

AUTOMATIC CONTROL MECHANISM.

Application filed February 4, 1926, Serial No. 85,957, and in Germany February 21, 1925.

My invention relates to automatic control mechanism in which a driving shaft is provided for actuating certain parts, such as for instance the tool in an automatic machine tool, the operative periods of the driven shaft being regulated by a control shaft.

In machine tools, as a rule, the control shaft performs a single rotation for each tooling operation and it will be understood that the control shaft will rotate very slowly for operations which take a considerable time, and it may thus occur that it does not regulate properly the periods of the several operations.

The control shaft is provided with a tappet by which clutches on the driving shaft are thrown in and out. When the control shaft rotates very slowly, its tappet is unable to perform its operations properly, and it is particularly unable to throw out the clutches on the driving shaft exactly in time, as the end of the tappet and the pawl with which it is in contact, do not separate immediately as would be the case with a more rapid rotation of the control shaft.

It has been proposed to overcome this drawback by connecting the pawl with a spring which throws it over as soon as it has been released. At the same time it is necessary to provide means for throwing out the pawl altogether when the tools are being set or certain operations are not to be performed. To this end the pawl was pivotally arranged on a support which was fulcrumed on the clutch control lever so that by throwing over this support the pawl was placed beyond the reach of the tappet. With this construction, two pivots are provided, one for the support and one for the pawl, and an exactly finished stop for securing the support in the inoperative position of the pawl.

It has also been proposed to provide a movable stop for the pawl which, when placed out of the way of the pawl, permits it to recede before said tappet. Both expedients are unsatisfactory on account of their complication. It is an object of my invention to provide a simpler and more reliable device.

To this end I provide the pawl with two contact faces for a spring actuated plunger,

these faces being so arranged that the plunger automatically holds the pawl in its operative and inoperative positions, as the case may be.

In the drawings affixed to this specification and forming part thereof a device embodying my invention is illustrated by way of example.

In the drawings

Fig. 1 is a section at right angles to the main and auxiliary control shafts showing the operating lever in elevation.

Fig. 2 is a section on the line 2—2 of Fig. 1.

Fig. 3 is a part elevation showing a separate pivotal pawl.

Figs. 4 to 8 illustrate various positions of the pawl on the operating lever, drawn to a larger scale.

Fig. 9 is a section on the line VIII—VIII in Fig. 1, also drawn to a larger scale and Fig. 10 is a development of a slot in one of the clutch sleeves.

Referring first to Figs. 1, 2 of the drawings, *i* is the driving shaft and *a* is the control shaft, *a'* is a disc secured on the shaft *a*, and *b* is a tappet which may be adjusted in a groove *a*² of the disc *a'*. The tappet *b* has an inclined operating face for a pawl on a lever *e*.

The lever is pivotally supported at *d*, and *f* is a spring tending to hold it against a fixed stop *g*. *h* is a pin at the opposite end of the lever *e* which engages a slot *k'* in a clutch sleeve *k* which is adapted to be displaced on the driving shaft *i*. As will appear from Fig. 9, the slot *k'* is extended at *x*, a gradient *y* being interposed between the extension and the slot. While the pin *h* is in the narrow portion of the slot, the sleeve *k* is held against displacement on the shaft *i*. A spring *k*² tends to hold the sleeve *k* engaged with teeth on a sleeve *l* which is keyed to the driving shaft *i*, and *i'* is a driven part free to rotate on the shaft which is in permanent mesh with teeth on the opposite end of the sleeve *k* but does not interfere with the axial displacement of the sleeve *k*. *m* is a cam on the sleeve *k* which is adapted to cooperate with the end of the lever *e* so as to expel the pin *h* from the slot *k'*.

c is a pawl fulcrumed on the end of the

lever *e* at *q* and adapted to cooperate with a plunger *r* which is guided in the boss *e'* at the end of the lever *i*. A spring *r'* tends to force the plunger *r* against the pawl *c*. *r'* is a plug closing the bore in the boss *e'* in which the plunger spring *r'* is concealed.

15 The pawl *c* is provided with a wedge shaped face *n* adapted to cooperate with the tappet *b*. *o* and *p* are faces inclined at an obtuse angle to each other on the pawl and adapted to cooperate with the end of the plunger *r*. *s* is a shoulder adjacent the face *p* and adapted to engage the inner end of the boss *e'*.

16 Fig. 3 shows the pawl in its inoperative position in which the plunger *r* engages its face *o*. The wedge *n* is in horizontal position and out of reach of the tappet *b*.

When it is desired to operate the clutch on the driving shaft *i*, the pawl *c* is thrown over into the position of Fig. 4, the plunger *r* turning the pawl on its pin *q* until the face of the plunger is in full contact with the face *p* of the pawl. When the wedge *n* of the pawl is engaged by the tappet *b*, as shown in Fig. 5, its wedge *n* ascends the inclined face of the tappet—which is rotated clockwise with the disc *a'*—and at the same time the pawl is turned on its pin *q* until its shoulder *s* engages the inner face of the boss *e'*. On further rotation of the shaft *a* the pawl *c* is raised, as shown in Figs. 5 and 6, and the lever *e* is turned about its fulcrum *d* against the action of the spring *f*.

17 The spring *k* is prevented from moving the sleeve *k* into engagement with the sleeve *l* while the pin *h* of the lever *e* is in its groove *k'* and the clutch sleeves will only become engaged when the pin *h* is withdrawn from the groove. This may be effected mechanically by the tappet *b*, a cam *m* on the sleeve *k*, or by hand with handle *e'* at the end of the boss *e'*.

18 The operation of this device is as follows: When the pawl *c* is not engaged by the tappet *b*, it assumes the inclined position illustrated in Fig. 4. When, on the clockwise rotation of the disc *a'* the tappet *b* engages the end of the wedge *n*, it will first turn the pawl *c* about its pin *q* until the shoulder *s* engages the face of the boss *e'* as shown in Fig. 5 and will then rise on the inclined face of the tappet and turn the lever *e* on its fulcrum *d* until the pin *h* at the opposite end of the lever has been moved out of the groove *k'*, whereupon the spring *k* will cause the sleeve *k* to become engaged with the sleeve *l* and will impart rotation to this sleeve and to the parts connected therewith, starting a given tooling operation. During the operation the wedge *n* is further raised on the tappet *b* until its end has reached the end of the tappet, as shown in Fig. 7. As soon as the wedge *n* has attained the edge of the tappet, the spring plunger *r*

will return the pawl into the position shown in Fig. 4 and, at the same time, the spring *f* will pull the pin *h* of the lever *e* back into its groove *k'* so that the clutch is thrown out and the sleeve *k* is no longer rotated by the shaft *i*.

When the tappet *b* turns the lever *e* on its pivot *d*, the pin *h* is moved out of the slot *k* so that the spring *k* is free to connect the sleeve *k* with the sleeve *l* and to start the prescribed operation through the medium of the part *i'*. However, the sleeve *k* is only permitted to perform one complete rotation at a time, the curve *k'* being so shaped as to throw out the clutch *l*, *k* at the end of each rotation. In order to prevent interference on the part of the pin *h*, a tappet *m* is provided which moves the pin *h* out of the groove *k'* before the clutch is thrown in.

It will be understood that on the anti-clockwise rotation of the sleeve *k* the extended end *x* of the slot *k'* will first be entered by the pin *h*, and, on further rotation of the sleeve *k*, it will be pushed aside by the pin *h* engaging the gradient *y*, and the sleeve will be disconnected from the teeth of the part *l*, be arrested by the pin when the rear end of the narrow slot portion abuts against the pin *h*, and remains stationary until the pin *h* is again moved out of the slot *k'* by the cam *b* lifting the end of the lever *e*.

The operation to be performed generally does not require a complete revolution of the sleeve *k*, notwithstanding provision is made that it should perform a complete revolution as it is desirable that it should return to its initial position. The cam *m* lags for an angle of about 180 deg. with respect to the rear end of the slot *k'*, so that, when the slot has moved through that angle, the cam *m* will strike the pin *h* and lift the pawl *c* quite clear of the tappet *b*.

I wish it to be understood that I do not desire to be limited to the exact details of construction shown and described, for obvious modifications will occur to a person skilled in the art.

I claim:

1. An automatic control mechanism comprising a driving shaft, a clutch on said driving shaft, a control shaft, a tappet on said control shaft, means adapted to be actuated by said tappet to operate said clutch, an adjustable pawl pivotally carried on said clutch-operating means, a projection on said pawl adapted to cooperate with said tappet, two contact faces on said pawl extending at an angle to each other, and a spring plunger slidably carried on said clutch-operating means and adapted to alternately engage said contact faces.

2. An automatic control mechanism comprising a driving shaft, a clutch on said driving shaft, a control shaft, a tappet on

said control shaft, means adapted to be actuated by said tappet to operate said clutch, an adjustable pawl pivotally carried on said clutch-operating means, a projection on said 5 pawl adapted to cooperate with said tappet, two contact faces on said pawl extending at an angle to each other, a shoulder on said pawl, a boss on said clutch-operating means adapted to be engaged by said shoulder, and a spring plunger slidably carried on said clutch-operating means and adapted to alternately engage said contact faces.

In testimony whereof I affix my signature.

KARL TESSKY.
